UNITED STATES PATENT OFFICE

2,479,479

HEATING STOVE AND AIR FEEDING
MEANS THEREFOR

John A. Doan, St. Louis, Mo.

Application October 20, 1944, Serial No. 559,547

2 Claims. (Cl. 126—77)

1

This invention relates to a heating unit, and more particularly to such a unit as a stove adapted for the heating of a room or the like.

A primary object of this invention is to provide an improved stove with means whereby the draft of the same is forced by natural thermal currents to pass over the top of the fire bed, rather than through the same, from the bottom, as is conventional practice.

An additional object of this invention is to provide such a stove with means for pre-heating the air utilized for combustion prior to its contact and mixture with the gases of combustion of the fire bed, whereby to insure a more efficient combustion, and resultant increase of heat conveyed to the area to be heated, rather than up the chimney or flue of the stove.

Still another object of this invention is to provide such a unit so designed as to more nearly complete the combustion of the fuel utilized therein, thus reducing the ash content.

Still another object of this invention is to provide a stove so designed as to omit controllable drafts below the fire bed, the drafts being wholly controlled by the upper draft of the stove.

Still another object is to provide a stove which will be sturdy and durable in construction, reliable and efficient in operation, and relatively simple and inexpensive to manufacture and install.

Other objects reside in the combinations of elements, arrangements of parts, and features of construction, all as will be more fully pointed out hereinafter, and shown in the accompanying drawings, wherein there is disclosed a preferred embodiment of this inventive concept.

In the drawings:

Figure 1 is a front elevational view of one form of stove embodying features of this invention.

Figure 2 is a side elevational view of the stove shown in Figure 1.

Figure 3 is an enlarged sectional view taken substantially along the line 3—3 of Figure 1, as viewed in the direction indicated by the arrows.

Figure 4 is an enlarged sectional view taken substantially along the line 4—4 of Figure 2, as viewed in the direction indicated by the arrows, and

Figure 5 is an enlarged sectional view taken substantially along the line 5—5 of Figure 2, as viewed in the direction indicated by the arrows.

Like reference numerals refer to like parts throughout the several views of the drawings.

Having reference now to the drawings, there is generally indicated at 10 a stove body, pref-

2

erably constructed of steel, or the like, and being comprised of side walls 11 forming an oval-shaped body portion, a bottom 12 and a top 13.

Positioned interiorly of the body wall 11 is a flange 14, secured thereto in any desired manner, upon which is adapted to rest a grate 15. Surrounding the interior of the body above the grate 15 and extending a substantial distance thereabove is a shell 16 forming an inner wall entirely surrounding the combustion chamber.

Positioned in the stove body below grate 15 is an ash receptacle 17, adapted to extend forwardly into a rectangular section 18 (see Fig. 5) of the stove body, which portion 18 is provided with a door 19 hinged, as at 20, and provided with a latch 21, adapted to permit the removal of the ash receptacle when the same is filled.

The stove body is adapted to be supported on legs 22, or the like.

Positioned above the upper extremity of inner wall 16 are two ducts or air vents 25, which may be integral with the stove body, or suitably secured thereto in any desired manner, and which extend from inlets 26 suitably positioned at spaced points on the front of the stove to outlets 27 positioned adjacent the rear of the stove, and terminating in downwardly turned elbows 29 (see Fig. 4).

The inlets of the ducts 26 comprise apertures having bars 30, or the like, positioned thereacross, which bars contain threaded apertures adapted to be engaged by the threads of bolts 31 (see Fig. 5) suitably secured to circular damper members 32 provided with handles 33. Thus, it will be seen that rotation of the handles 33, through the coaction of the bolts 31 and their associated threaded apertures, serves to open or close the inlets 26 of the members 25, the quantity of air admitted thereto being varied in accordance with the spacing of the dampers 32 from the inlets.

The outlets 27 are spaced a substantial distance apart, beneath an arcuate baffle 35 closing the rear portion of the stove body 10, and being positioned therebelow, a second vertical baffle 36 being positioned at a mid-point thereof and extending to the top of the stove (see Figs. 3 and 4). A flange 37 surrounds an aperture 38 in the rear of the stove body above the baffle 35, and connects with a flue or outlet 39.

A second flange 40 surrounds an aperture or opening 41 on the top of the stove 13, in front of the baffle 35, which aperture provides a means for inserting fuel into the stove. A cover 42 provided with a flange 43 of less diameter than the flange 40, and having a handle 44, is adapted

securely to close the opening 41 when the use of the same for insertion of fuel into the structure is not necessary.

Now, from the foregoing the operation of the device should be readily understandable. Fuel is positioned on grate 15, and ignited in any suitable manner, and the drafts 32 adjusted to open position. The air is then sucked inwardly through inlets 26, air ducts 25 and pass outwardly through outlets 27 in a downward direction. As the air passes over the combustion chamber and the fire therein, it is pre-heated to a relatively great extent, in such manner that when it emerges through the outlets 27, it readily ignites when mixed with the gases of combustion emanating from the fire. The draft then passes over the fire bed, outwardly and upwardly over the baffle 35 and around the sides of the baffle 36, finally escaping through the aperture 38 to the flue 39. By this method, and due to the fact that the air is heated to a burning stage before it is passed to the fuel bed, the fuel is caused to burn downwardly instead of upwardly. Under the reverse conditions of burning fuel, that is, with an under draft, the gases and smoke from the fuel are drawn upwardly and forced out of the chimney unburned, thus causing a considerable waste of fuel, as a large percentage of the heat from the fuel is contained in the smoke and gases. By the instant method, it will be seen that the air is circulated downwardly through the fuel, adjacent the inlets, and finally upwardly therethrough toward the front or cooler portion of the fire bed, thus effecting a relatively greater combustion of the fuel contained in the stove.

From the foregoing it will now be seen that there is herein provided an apparatus accomplishing all the objects of this invention and others, including many advantages of practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. A stove comprising a body, a grate in said body, a sheet metal lining in said body spaced equidistantly from the walls thereof and having integral upper and lower flanges engaging said body to provide a dead air space between said lining and body, said lining positioned above said grate forming the walls of a combustion chamber, an outlet for combustion products in the top of said body, a horizontal baffle extending between and being joined to opposite sides of said body beneath said outlet, a vertical baffle medially of the front edge of said horizontal baffle and engaging said top, and air inlet conduits extending above said lining and about the walls of said body, said conduits having discharge openings beneath said horizontal baffle and directed downwardly toward said grate.
2. The combination of claim 1 wherein said horizontal baffle is concaved downwardly from its longitudinal medial line.

JOHN A. DOAN.
